LATCH LOCK FOR MINE CARS

Robert A. Shields, Bloomsburg, Pa., assignor to
American Car and Foundry Company, New
York, N. Y., a corporation of New Jersey

Application September 1, 1942, Serial No. 456,867

16 Claims.

(C.I. 105—286)

This invention relates in general to latch locks for mine and industrial cars and in particular to automatic latch locks for use with drop bottom mine cars.

Drop bottom mine cars as built for a number of years have utilized a hook and arm arrangement to lock the rear door of the car and permit its tripping at the dump pit. However, considerable trouble has been due to the fact that the latch was operated in the mine by stone or lumps of coal which may have fallen along the track. Operation of the latch in the mine necessitated either a complete unloading of the car or a dragging of the car with door down over the ties, switches, etc. In any case considerable delay and inconvenience was caused whenever a latch was accidentally operated. Such delay and inconvenience is multiplied many times in case the so-called 1-2-3 car is used, that is, a car in which all doors drop when the rear latch is operated and drag on the ties until the first door reaches the pit edge. Recently locking dogs have been used to prevent operation of the hook arm, but frequently these dogs vibrate to an off position and required the presence of an extra man at the dump station for the sole purpose of operating the dogs. Frequently the operator would forget to throw the dog to the locked position, with the result that the hook arm was not locked and the delays due to accidentally dumped doors still occurred. It is an object, therefore, of the present invention to provide an automatic safety latch for the main latch or hook arm of a drop bottom mine car.

A further object of the invention is the provision of a latch for the rear door of a drop bottom mine car in which the latch parts must move substantially simultaneously in two directions in order to unlatch the door.

A still further object of the invention is the provision of an automatically operated safety latch movable by a thrust acting substantially normal to the car side.

A yet further object of the invention is the provision of a latch for drop bottom mine cars which can be operated to a released position only by independent forces acting substantially at right angles to each other.

These and other objects of the invention will be apparent to persons skilled in the art from a study of the following description and accompanying drawings, in which

Figure 1 is an elevational view showing a mine car passing the dumping pit;

Fig. 2 is an end view of the car with the improved latch arrangement;

Fig. 3 is an end view with parts of the latch mechanism in section in order to better disclose the construction;

Fig. 4 is a plan view of the latch and trackside operator;

Fig. 5 is a side view similar to Fig. 1 but showing a partial car and in the position leaving the dumping pit;

Fig. 6 is an end view similar to Fig. 3 but showing a slight modification, and

Fig. 7 is a sectional view taken substantially on line 1—1 of Fig. 6.

15 Referring now to the drawings in detail, it will be seen that a mine car of more or less conventional construction has been disclosed. The car is constructed with sides 2 attached to and supported by sills 4 and bracing gussets 6. The side walls are joined by a front end wall 8 and a rear end wall 10, while the sills are joined together and to the end walls by front and rear bumpers 12 and 14 respectively. The car is supported on tracks T by wheels W which project into the lading body of the car and are covered by wheel hoods 16. The space between the side sills is closed by drop bottom doors 18, 19 and 20 located respectively adjacent the front, intermediate and rear portions of the car. These doors are hinged by hinge rods 22 carried by the side sills and have their adjacent edges engaging so as to form a substantially continuous bottom when the doors are closed. The rear door is provided with a hook lug or tongue 24 extending rearwardly from the door and adapted to be engaged by a hook H.

The hook H, as shown in Figs. 1 to 5 inclusive, is fastened by any suitable means, such as rivets 26, to the vertically extending leg 28 of an angle form member having the other leg 30 positioned

40 uppermost and directed outwardly from the end of the car. The angle member or hook arm is pivoted as at 32 by means of a bracket 34 fastened to the end wall of the car. The hook arm and hook are constantly urged toward latched position

45 by means of a spring 36 guided by bolt 38, all as clearly shown in Fig. 2. The hook arm extends laterally through a slot formed in end wall brace 40 and has its outer end reinforced by means of an angle having vertical leg 42 and hori-

50 zontal leg 44 so arranged and attached to legs 30 and 28 as to form a box section on the hook arm outwardly of the hook H. As most clearly shown in Fig. 3 a backing plate 46 is welded or otherwise secured in place within the box section end

55 of the hook arm and forms an abutment for one

end of a spring 50, the other end of which fits within a cup like member 52 slidably within the box like section of the hook arm. This cup like member 52 bears against the lower end of safety latch bar 54 pivoted as at 56 on upstanding ears 58 welded or otherwise secured to the hook arm on either side of a slot 60 formed in the horizontal leg 30. Movement of the safety latch bar is controlled by a plunger or latch operator 62 slidably mounted within the box section hook arm and held in place by a bolt or rivet 64 extending through the legs 28 and 42 of the angles forming the box section end of the hook arm. A slot 66 is formed in the plunger in order that it may move inwardly over the bolt or rivet 64. The customary guide 68 for the hook arm end is modified by forming an additional offset therein as at 70 in order to form a keeper beneath which the upper end of the safety latch bar may swing in order to prevent lifting of the hook arm. The guide strap is riveted or otherwise secured to the car by short rivet 72 and long rivet 74. The lower end 76 of the guide strap may be either directly attached to the end wall of the car or twisted to fit underneath the sloping portion of the side wings as clearly shown in Fig. 4.

It will be obvious from the preceding that the safety latch has been shown as applied to a substantially conventional drop bottom mine car with the conventional hook arm modified slightly to accommodate the safety latch. It will also be obvious that the car can operate over the regular trackage and function exactly as a standard car would now function. In order to operate the safety latch, however, the hook tripping ramp R located adjacent the forward edge of the pit P is modified by addition of a plate 78. This plate is attached to the inclined portion 80 of the tripping ramp and is provided with an approach surface 82 and a curved leaving surface 84 with the surface intermediate these surfaces of sufficient width and inclination as to hold the plunger 62 in its innermost position within the box like section of the hook arm. As clearly shown in Fig. 2, as the car would move toward the dumping pit in the direction of the arrow of Fig. 1, the plunger 62 would strike the approach surface 82 and be moved inwardly and held inwardly by the intermediate surface, while the inclined part 80 of the ramp R caused the hook arm to be raised, thus releasing the tongue 24 of the rearmost door. Movement of the plunger 62 inwardly will, of course, compress spring 50 and rock the safety latch bar 54 so as to bring the upper end of the bar from beneath the ledge 70 of the guide strap. After the lading in the car has dumped the doors are closed by inclined rails 86 and in order that the hook arm may again engage the tongue 24, it is necessary to provide a second hook arm tripping ramp R' located adjacent the far end of the dumping pit as shown in Fig. 5. Since this tripping ramp is identical with that at the approach end of the pit, the same numerals have been applied but with a prime attached thereto. It will be seen from Fig. 5 that the end of the door closing arm 86 is sufficiently long as to hold the rearmost door closed until the hook arm has dropped off of the operating ramp R' and fallen into the door engaging and latched position shown in Fig. 3. From the preceding it will be seen that the standard installation need be modified only to the extent of adding the safety latch to the hook arms and providing the operating plates 78 on the tripping ramps R and adding a similarly equipped ramp R' at the leaving end of the pit.

In some cases it may be desirable to eliminate the tripping ramp R' and this may be accomplished as shown in Figs. 6 and 7 wherein all parts duplicating those of Figs. 1 to 5 have been indicated by the same numerals. In this modification the hook H is pivotally mounted on leg 28 by means of a pivot, bolt or other device 90. Swinging of the hook is controlled by means of plates 92 riveted or otherwise secured to the hook arm and carrying at their lower end a bolt 94 which extends through a slot 96 formed in the hook. A spring 98 is provided having one end bearing beneath the leg 30 of the angle formed hook arm and the other end bearing against a shoulder formed on the hook H. This spring is preloaded in order to hold the hook in the full line position of Fig. 6. With this hook arrangement lifting of the hook arm, when permitted by the safety latch, will move the hook exactly as it would move if it were rigid with the hook arm since the bolt 94 is in the upper end of the slot 96. When, however, the hook arm is in its down position and held in the down position by the safety latch, the hook may swing to the line and dash position of Fig. 6 by compressing the spring 98. Such swinging would be caused by the door tongue 24 riding along the incline 99 of the hook as the rear door was forced closed by the closing ramp 86. As soon as the door is raised sufficiently the hook would be snapped to its full line position by the spring 98 and the door would be fully latched.

It will be seen that it is impossible for the doors to be unlocked as in the past by merely a lifting force applied to the hook arm, since the lifting of the hook arm is prevented due to the safety latch bar 54 acting as a strut positioned between the ledge 70 of the guide strap and the hook arm. Movement of the safety latch to a released position will not of itself release the door but will only move the safety latch from beneath the over-hang 70. In order to release the rear door and permit movements of the hook arm to the position shown by line and dash of Figs. 2 and 4 it is necessary for the plunger to be moved inwardly prior to a vertical lifting of the hook arm. Furthermore, the plunger must be held in at least until the hook arm has lifted a considerable amount, otherwise the safety latch would again engage beneath the ledge 70. In other words, the hook cannot be released except by two forces acting substantially at right angles to each other, one substantially horizontal force operating the plunger and the other a vertical force operating the hook arm. As clearly shown in the drawings, considerable clearance is left between the upper end of the safety latch bar and the ledge 70. This clearance is of insufficient amount to permit release of the hook from the tongue 24, yet is sufficient to permit slight movement of the hook arm, thus allowing it to clear certain track-side obstructions without danger of damaging the hook mechanism.

While the improved latch arrangement has been described more or less in detail with specific reference to two forms, it will be obvious that various modifications and arrangements of parts other than those shown and described may be made and all such modifications and new arrangements of parts are contemplated as will fall within the scope of the appended claims defining my invention.

What is claimed is:

1. A dump car comprising, spaced apart lading retaining walls, doors closing the space between

said walls and hinged to swing downwardly to discharge the lading of the car, a main latch carried by the car and normally retaining at least one of the doors in closed position, and an automatically operated safety latch carried wholly by said main latch and engageable with a fixed part of the car to normally hold said main latch in door retaining position.

2. A dump car comprising, spaced apart lading retaining walls, doors closing the space between said walls and hinged to swing downwardly to discharge the lading of the car, a main latch carried by the car and normally retaining at least one of the doors in closed position, and an automatically operated safety latch normally holding said main latch in door retaining position, said safety latch being mounted on said main latch and movable therewith after being released.

3. A dump car comprising, spaced apart lading retaining walls, doors closing the space between said walls and hinged to swing downwardly to discharge the lading of the car, a main latch carried by the car and normally retaining at least one of the doors in closed position, said main latch moving to release the door upon application of a substantially vertically acting force, and a safety latch normally blocking movement of said main latch and operable upon application of a substantially horizontally acting force to release the main latch for movement.

4. A dump car comprising, spaced apart lading retaining walls, doors closing the space between said walls and hinged to swing downwardly to discharge the lading of the car, a main latch carried by the car and normally retaining at least one of the doors in closed position, said main latch moving to release the door upon application of a substantially vertically acting force, and a safety latch normally blocking movement of said main latch and operable upon application of a substantially horizontally acting force to release the main latch for movement, said safety latch being mounted on said main latch and engaging a fixed part of the car to lock said main latch in door retaining position.

5. A dump car comprising, spaced apart lading retaining walls, doors closing the space between said walls and hinged to swing downwardly to discharge the lading of the car, a hook engaging at least one of the doors to retain the same in closed position, a latch arm pivotally mounted on the car and carrying said hook and formed with a hollow end portion, a safety latch bar pivotally mounted on said latch arm and having one part extending into said hollow end portion and another part extending laterally to engage a fixed part of the car to lock said latch arm and hook in door retaining position, and plunger means slidible within said hollow arm and operable to swing said safety latch bar out of engagement with said fixed part of the car.

6. A dump car comprising, spaced apart lading retaining walls, doors closing the space between said walls and hinged to swing downwardly to discharge the lading of the car, a hook engaging at least one of the doors to retain the same in closed position, a latch arm pivotally mounted on the car and carrying said hook and formed with a hollow end portion, a safety latch bar pivotally mounted on said latch arm and having one part extending into said hollow end portion and another part extending laterally to engage a fixed part of the car to lock said latch arm and hook in door retaining position, and plunger means slidible within said hollow arm

and operable to swing said safety latch bar out of engagement with said fixed part of the car, said hook being pivotally mounted on said latch arm and movable toward door releasing position independently of said latch arm whereby said door may be moved to closed position irrespective of the position of said safety latch bar.

7. A dump car comprising, spaced apart lading retaining walls, doors closing the space between said walls and hinged to swing downwardly to discharge the lading of the car, a latch arm pivotally carried by the car and a hook for retaining a door in closed position and being pivotally carried by said latch arm and movable relative thereto.

8. A dump car comprising, spaced apart lading retaining walls, doors closing the space between said walls and hinged to swing downwardly to discharge the lading of the car, a latch arm pivotally carried by the car, a hook pivotally carried by said latch arm and movable relative thereto under action of a closing door, and spring means interposed between parts of said arm and hook and constantly urging said hook toward door engaging position.

9. A dump car comprising, spaced apart lading retaining walls, doors closing the space between said walls and hinged to swing downwardly to discharge the lading of the car, a latch arm pivotally carried by the car, a hook for retaining a door in closed position and being pivotally carried by said latch arm and movable relative thereto, and a safety latch preventing accidental operation of said latch arm to release the door.

10. A dump car comprising, spaced apart lading retaining walls, doors closing the space between said walls and hinged to swing downwardly to discharge the lading of the car, a main latch carried by the car and directly retaining at least one of the doors in closed position, said main latch including a latch arm and a hook engageable by the door, safety means preventing accidental movement of said latch arm, and means permitting relative movement between said latch arm and hook when the latter is acted upon by the closing door.

11. In a device of the character described, the combination of a dump car having spaced apart lading retaining walls and doors closing the space between the walls and hinged to swing downwardly to discharge the lading of the car, a main latch carried by the car and retaining at least one of the doors in closed position, a safety latch carried by the car and normally preventing movement of said main latch, means for operating said main latch, and additional means for operating said safety latch and holding the same in released position during operation of said main latch by said first named means.

12. In a device of the character described, the combination of a dump car having spaced apart lading retaining walls and doors closing the space between the walls and hinged to swing downwardly to discharge the lading of the car, a main latch carried by the car and retaining at least one of the doors in closed position, a safety latch carried by the car and normally preventing movement of said main latch, means for lifting a part of said main latch to release said one door for opening movement, and means acting axially of said main latch part to operate said safety latch prior to lifting of said main latch part.

13. In a device of the character described, the combination of a dump car having spaced apart lading retaining walls and doors closing the space

between the walls and hinged to swing downwardly to discharge the lading of the car, a main latch carried by the car and retaining at least one of the doors in closed position, a safety latch carried by the car and normally preventing movement of said main latch, means for moving said main latch to release said one door for opening movement, and additional means acting upon a part associated with said main latch to operate said safety latch prior to the moving of said main latch by said first named means.

14. In a device of the character described, the combination of a dump car having spaced apart lading retaining walls and doors closing the space between the walls and hinged to swing downwardly to discharge the lading of the car, a main latch carried by the car and retaining at least one of the doors in closed position, a safety latch carried by the car and normally preventing movement of said main latch, means acting in one direction upon a part of said main latch to move the same and release said one door for opening movement, and additional means acting in another direction to operate said safety latch prior to movement of said main latch part to release said one door.

15. A dump car comprising, spaced apart lading retaining walls, doors cooperating with said

walls to form a lading retaining body and being movable to an open position to discharge lading from the body, a main latch carried by the car for normally retaining at least one of the doors in closed position and movable to released position permitting movement of the door to an open position, and an automatically operated safety latch normally retaining said main latch in door retaining position and movable in the plane of said main latch to a released position permitting movement of said main latch to released position.

16. A dump car comprising, spaced apart lading retaining walls, doors cooperating with said walls to form a lading retaining body and being movable to an open position to discharge lading from the body, a main latch carried by the car for normally retaining at least one of the doors in closed position and movable to released position permitting movement of the door to an open position, and an automatically operated safety latch normally retaining said main latch in door retaining position and movable to a released position permitting movement of said main latch to released position, said latches being operable in sequence and by forces acting substantially at right angles to each other.

ROBERT A. SHIELDS.
